DANIEL K. POPE, OF CLEVELAND, OHIO

SPRING COVER

Application filed May 28, 1929. Serial No. 366,674.

This invention relates to spring covers of the type employed for protecting vehicle leaf springs from the moisture and for supplying a lubricant between the leaves of the spring.

5 The present invention has for its object to provide a spring cover which is inexpensive to manufacture and which conforms accurately to the contour of the spring to which it is applied.

10 A further object is to provide a spring cover which is formed of a vulcanizable material and which is water-proof and resistant to oils and greases.

15 A further object is to provide a one-piece spring cover in which a bulge is provided to accommodate projecting portions of the rebound clip.

20 A further object is to provide a one-piece cover free from all joints and seams which is molded and vulcanized to a form such that it will conform accurately to the spring to which it is applied.

25 With the above and other objects in view, the invention will be said to comprise the spring cover as illustrated in the accompanying drawing hereinafter described and particularly set forth in the appended claims, together with such variations and modifications thereof as will be apparent to one skilled in the art to which the invention appertains.

30 Reference should be had to the accompanying drawing forming a part of the specification in which:

35 Figure 1 is a sectional view showing the cover applied to a spring.

Fig. 2 is a bottom plan view of the spring with a cover applied thereto.

Fig. 3 is a section taken on the line indicated at 3—3 in Fig. 1.

40 Fig. 4 is a section taken on the line indicated at 4—4 in Fig. 3.

Fig. 5 is a fragmentary section showing the material of the cover.

45 Fig. 6 is a fragmentary section showing a modification of the material of the cover.

The cover of the present invention is shown applied to a leaf spring 1 composed of superposed leaves 2 which are of gradually decreasing length from the top leaf to the bottom leaf of the spring. Leaf springs em-

ployed for supporting automobile bodies are provided on the tapering end portions thereof with rebound clips, each of which consists of a U-shaped member 3 which fits upon the bottom and sides of the spring with its spaced arms projecting above the top of the spring.

55 The projecting ends of the U-shaped member 3 are connected by a clamping bolt 4 which has a head engaging the outer face of one of the arms and a nut 6 engaging the outer face of the other of the arms. The spring cover which is indicated generally by the reference numeral 7 is of substantially trapezoidal form so that it is adapted to wrap about and enclose a tapered end portion of a leaf spring and within the cover, there is a longitudinally extending pad 8 of felt or other suitable absorbent material which is held in contact with overlapping leaves along the underside of the spring.

60 At the ends thereof, the cover is provided with sealing strips 9 formed of felt or similar material secured to the inner face of the cover along the end edges thereof. The body 8 and sealing strips 9 are preferably impregnated 65 with a lubricating composition which is non-fluent at any atmospheric temperature to which they may be subjected in use so that the lubricant is transferred from the pad to the surfaces of the leaves only by frictional engagement of the leaves with the pad in the flexing of the spring. The lubricating composition also serves to render the pad and sealing strips waterproof so that moisture will not be drawn into them by 70 capillary attraction.

75 The cover of the present invention is made from a vulcanizable composition, the cover being made from a flat piece of unvulcanized material which is molded to the desired form in a vulcanizing press. The material from which the cover is made may be a rubber composition which is resistant to the deteriorating action of oils and greases, such compositions now being commercially available. 80 The rubber composition may be strengthened by mixing fibrous material therewith, the fibrous material being indicated by the reference numeral 10 in Fig. 5. The composition may, if desired, be in the form of sheet 85 90 95 100

material reinforced with a loosely woven fabric 11 such as shown in Fig. 6, the fabric being sufficiently stretchable to permit a flat piece of the material to be molded to the desired form. If desired, any suitable rubber composition may be employed and a flexible waterproof and oil resistant coating 12 of varnish applied to the opposite side thereof as shown in Figs. 5 and 6.

10 In vulcanizing the cover, a transversely extending bulge 13 is molded therein and this bulge is of a size and shape to accommodate the projecting portions of the rebound clip as shown in Fig. 3 of the drawing.

15 In forming the cover, a rib 14 is molded on the outer side thereof parallel but spaced from one edge of the cover, the rib being molded around a reinforcing rod 15. At the opposite edge of the cover, a bead 16 is molded about a reinforcing rod 17. The edge portion of the cover upon which the bead 14 is molded extends substantially the entire distance across the bottom of the spring and the edge of the cover upon which the bead 16 is molded extends partially across the underside of the spring overlying the first mentioned edge, so that the two beads extend parallel with each other along the length of the spring, the beads being preferably spaced 25 apart a sufficient distance to permit the slack in the cover to be taken up as the lubricating pad is compacted.

30 The cover is secured in place on the spring by means of spring fasteners 18 which are connected to the reinforcing rods 15 and 17, the reinforcing composition being removed from the rods at spaced points along the length of the cover. Each of fastening elements 18 is formed of a spring wire which 35 is coiled about one of the rods, extends longitudinally of the rod from its point of attachment to a spring coil 19, the opposite end of the wire extending from the coil 19 in the form of an L-shaped arm 20 which terminates 40 in a hook 21 which engages the other rod.

45 The fastening elements which are described and claimed in my copending application Serial No. 345,971, filed March 11, 1929, which has matured into Patent No. 1,799,864, dated 50 April 7, 1931, serve to maintain a spring tension on the cover and to automatically take up any slack which would otherwise form in the cover due to the compacting of the lubricating pad.

55 It will be apparent that the cover of the present invention may be formed completely in the vulcanizing press with the exception of the attachment of the fastening device, the bulge to accommodate the spring clip 60 being molded in the cover in the vulcanizing press, and reinforcing rods being embedded therein so that no sewing or other finishing operations are required.

What I claim is:

65 1. A one-piece molded spring cover com-

posed of an oil resistant and waterproof vulcanized rubber composition and of a size and shape to be wrapped about and enclose a vehicle leaf spring with the opposite side edges of the cover overlapping along the bottom of the spring, said cover having a molded longitudinal bead formed along one side edge thereof, and a second longitudinal bead molded on the outer face of the cover parallel with and spaced from the opposite edge to provide a flat edge portion which is overlapped by the beaded edge whereby said beads are positioned in parallel spaced relation along the under side of the spring, and resilient fastening means detachably connecting said beads to maintain a tension on the cover.

70 2. A one piece molded spring cover composed of an oil resistant and waterproof vulcanized rubber composition and of a size and shape to be wrapped about and enclose a vehicle leaf spring with the opposite side edges of the cover overlapping along the bottom of the spring, said cover having a molded tubular bead formed along one side edge thereof, and a second tubular bead molded on the outer face of the cover parallel with and spaced from the opposite side edge, portions of said beads being cut away at intervals along the length thereof to provide openings, a reinforcing rod fitting in each of said beads and extending across the openings thereof, and resilient fastening members connecting the rods at spaced intervals along the length of the cover and engaging said rods in said openings.

75 3. A spring cover adapted to be wrapped about and enclose a vehicle leaf spring and formed in one piece of flexible vulcanizable sheet material, said cover having molded longitudinal beads adjacent the opposite edges thereof, one of said beads being at one edge of the cover and the other being parallel with and spaced from the opposite edge, whereby the beaded edge may overlap the opposite edge to dispose the beads in parallel spaced relation beneath the spring, a reinforcing rod embedded in each bead to stiffen the cover and prevent sagging thereof along the bottom of the spring, and resilient fastening elements connecting said rods at spaced points along the length of the cover to maintain a tension on the cover.

80 In testimony whereof I affix my signature,

DANIEL K. POPE.
